Primary Examiner — Khawaja Anwar*Assistant Examiner* — Mojtaba Tehrani(74) *Attorney, Agent, or Firm* — Bayramoglu Law Offices LLC(57) **CLAIM**

The ornamental design for a folding bipod, as shown and described.

DESCRIPTION

FIG. 1 is a perspective view of a folding bipod showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the folding bipod, in folded position, in condition of use;

FIG. 9 is a perspective view of the folding bipod, in deployed position, in condition of use; and,

FIG. 10 is a partial an enlarged view of the indicated area "A" in the FIG. 9.

The broken line showing of the rifle is for the purpose of illustrating the environmental structure and forms no part of the claimed design.

The dot-dash broken lines indicating an enlargement portion of the design form no part of the claimed design.

1 Claim, 10 Drawing Sheets(56)
